UNITED STATES PATENT OFFICE.

DAVID G. DEE, OF CHICAGO, ILLINOIS, ASSIGNOR, BY MESNE ASSIGNMENTS, TO
ROCHESTER H. ROGERS, OF ROCHESTER, NEW YORK.

LOCAL FIRE-ALARM SYSTEM.

1,221,032.

Specification of Letters Patent.

Patented Apr. 3, 1917.

Application filed December 19, 1914. Serial No. 878,037.

To all whom it may concern:

Be it known that I, DAVID G. DEE, a citizen of the United States, residing in Chicago, county of Cook, and State of Illinois, 5 have invented certain new and useful Improvements in Local Fire-Alarm Systems, of which the following is a specification.

This invention relates to local fire alarm systems, which are complete in themselves, 10 as distinguished from a fire alarm system having central office connections; and while the present system may be provided with such central office connections, its primary function and purpose is to provide an interior or local fire alarm which may be operated for indicating within the building the locality of a fire.

The present system is supplied with a trouble or test circuit, whereby the alarm 20 system may be tested, said trouble or test circuit being provided with a trouble alarm which will operate when any condition of trouble exists in the alarm circuit.

With the above and other objects in view, 25 as will be hereinafter apparent, this invention consists in the construction, combination and arrangement of parts all as hereinafter more fully described, claimed and illustrated in the accompanying drawings, wherein—

30 Figure 1 is a diagrammatic view of a complete installation, illustrating the circuits, the circuit controls and the signal sending and receiving mechanisms, prior to any operation on the part of the signal sending mechanisms or boxes;

35 Fig. 2 is a similar view and illustrates similar elements as positioned when a box is operated.

In a complete installation of the present 40 invention, an alarm battery B, designed primarily for use over the alarm circuit and which constitutes a source of current supply for said alarm circuit, is provided, and has the line wire b connected to the positive 45 pole thereof and the line wire b' connected to the negative pole. The line wire b has a plurality of signal receiving devices 7 and signal sending devices or boxes 8 arranged in series therein, the details of said 50 signal sending and said signal receiving mechanisms to be hereinafter more fully referred to. The wire b'', which constitutes a continuation of the wire b, extends to the 55 line wire b' connects directly with the spring

contact 10, said contact being bodily stationary. Normally held in operative engagement with the contact 9 is a similar contact 11, which contact 11 is in circuit with the wire b''', by means of a connection 12. 60 The wire b'''' is electrically connected with a spring contact 13.

Normally, as illustrated in Fig. 1, the alarm circuit is open, and there is no battery flow from the supply B through the 65 wires b, b', b'' and b''''. However, when the signal sending mechanisms 8 are operated, the first step of operation thereof causes the spring contacts 10 and 13 to connect, thereby causing a flow from the positive pole of the 70 battery B, through the wire b, the signal receiving and sending mechanisms 7 and 8 respectively, the wire b'', the contacts 9 and 11, through the wire 12 and the wire b''', the contacts 13 and 10, the wire b', to the negative side of the battery B (see Fig. 2). The signal sending mechanisms 8, by their continued operation, operate the signal receiving mechanisms 7 over the alarm circuit thus built up. The circuit control which closes 80 the circuit by bringing the contacts 10 and 13 together, comprises a relay which normally is controlled by the action of the signal sending mechanism, but in case of trouble, such as the breaking or grounding of one of 85 the wires b, b', b'' and b''', it operates to give a trouble alarm. This relay R comprises a coil 14 and an armature 15, said armature carrying the spring contact 13 and also the spring contacts 13' and 16, said contacts 13, 13' and 16 being insulated one from the other, as illustrated in the drawings. When the armature is held up, as illustrated 90 in Fig. 1, the contact 13 is elevated from the contact 10, whereas when the armature 95 falls away, as illustrated in Fig. 2, the spring contact 13 is brought into engagement with the spring contact 10, establishing the alarm circuit. The contact 13' coöperates with a stationary spring contact 10', said contact 13' being in circuit with the wire b''', and the contact 10' being in circuit with the wire b'. Thus, should the contacts 10 and 13 fail in their coöperation, the contacts 10' and 13' will complete the alarm circuit, 100 and vice versa, thereby doubly insuring the completion of the alarm circuit.

The trouble or test circuit is provided with two sources of battery supply, T and T', being arranged to connect with a switch 110

17, said switch being operable to connect with either one or the other of said batteries. A line wire t extends from the switch 17 to the spring contact 16 carried by the armature 15, and has a trouble signal 18 in series therein. The spring contact 16 is arranged to coöperate with a stationary spring contact 19, which contact is connected by means of the wire 20 to the wire t' , which is connected to the positive side of both batteries T and T' . This wire t' connects with one terminal of the coil 14 of the relay R , while the other terminal of the coil 14 is connected by a wire t'' to a wire t''' , which terminates in a stationary spring contact 21, located to coöperate with the spring contact 13. This wire t''' also terminates in a spring contact 22, which is arranged for coöperation with a movable spring contact 23.

Under normal conditions, that is to say, prior to any operation of the signal sending mechanisms 8, the relay R is energized from either of the trouble or test batteries T , T' , dependent upon the location of the switch 17, and the current flow is from the positive side of this battery, through the wire t' , the coil 14 of the relay R , the wire t'' , the spring contacts 13 and 21, through the wire b''' , the wire 12, the contacts 11 and 9, the wires b'' , the signal sending and signal receiving mechanisms 8 and 7, the wire b , and through the wire t , which is connected to the wire b , to the negative side of the battery T or T' . In this manner, a flow sufficient to energize the relay R and hold its armature 15 passes through the test circuit so established, and should a wire in this test circuit be broken, the armature 15 will fall away, assuming the position shown in Fig. 2. If this occurs, the contacts 13 and 21 will be separated and the contacts 13 and 10, and 13' and 10', and 16 and 19, will be brought together. When the contacts 16 and 19 are brought together, the current flows from the positive side of either battery T or T' , through the wire t' , through the wire 20, through the contacts 19 and 16, the wire t , the trouble or test signal 18, and through the switch 17 to the negative side of the battery T or T' , causing the trouble or test signal to operate, indicating that trouble exists in the alarm circuit. It is manifest that the relay is completely removed from the circuit, by reason of the fact that the wire t'' , connected to one terminal of the coil 14 of said relay, ends in the open connection 13 and 21 when the armature has fallen away, or in the open connection between the contacts 22 and 23.

By reference to the figures of the drawing, it will be seen that, irrespective of the position of the relay or the condition of the circuits, the contacts 22 and 23 are always separated, and the contacts 9 and 11 are in

engagement; so that the test circuit normally established by the relay R and including the signal sending and receiving mechanisms 8 and 7, is always complete through the contacts 9 and 11, and is not affected by the contacts 22 and 23 except for re-setting the relay after trouble or a test, which operation will now be described. When the system is in the condition shown in Fig. 1, the pressure placed upon the button 24, carried by the contact 11, breaks the connection between the contacts 9 and 11. This breaks the test circuit, which causes a separation of the contacts 13 and 21, thereby breaking the test circuit, which normally is established by the relay R from either battery T or T' through the wire t , b , the signal sending and receiving mechanisms 8 and 7, wire b'' , contacts 9 and 11, wire b''' , contacts 13 and 21, wire t'' , coil 14 of the relay, wire t' , and either of the batteries T or T' , in that the connection between the wires b'' and b''' is broken. This causes the armature 15 of the relay to fall away, to cause the contacts 13, 13' and 16, carried by said armature, to assume the positions shown in Fig. 2. In this manner, the trouble or test alarm 18 is operated, and the relay assumes the position shown in Fig. 2, it having been completely removed from the circuit; and when pressure is removed from the button 24, the contacts 9 and 11 immediately come together. In order to re-set the mechanism, either after operating the test button 24 or after an alarm, the spring contact 23 is provided with a button 25 which constitutes the re-set button. By bringing the spring contacts 22 and 23 together, the current flow is from the positive pole of the battery B , through the wire t , either of the batteries T or T' , through the wire t' , through the coil 14 of the relay R energizing the same, through the wire t'' , through the wire t''' , the contacts 22 and 23, the wire b''' , the contacts 10 and 13, and finally through the wire b' to the negative side of battery B . The combined action of one or the other of the batteries T or T' and the alarm battery B , overcomes the inertia of the armature 15 of the relay R , and starts to draw the same upwardly. The first movement on the part of the armature 15 breaks the connection between the contacts 13 and 10, 13' and 10', and 16 and 19, and causes a flow from the positive side of either battery T or T' , through the wire t' , coil 14 of the relay R , wire t'' , to and through the wire t''' , through the contacts 22 and 23 to the wire 12, and thence through the contacts 11 and 9 to the wire b'' , through the signal receiving and sending mechanisms 7 and 8, the wire b , the wire t , and thence through the switch to the negative side of either battery T or T' , completing the setting of the relay.

The trouble alarm mechanism 18 is either an electrical vibrating bell, a buzzer, or a similar register, while the signal receiving mechanisms 7 of the alarm circuit are either 5 electro-mechanical gongs, vibrating bells, horns or any other suitable signal receiving mechanisms, such as registers or other devices.

The signal sending mechanisms 8, however, are arranged to send a code signal over 10 the alarm circuit when built up, and comprise for that purpose a code wheel 26, of any suitable construction, which operates upon a pen 27. This pen is insulated from 15 and is secured to a spring contact 28, which spring contact is connected by a wire 29 to the connecting wire *b*, as is also a spring contact 30, which is connected directly to the wire *b* entering the box containing the signal sending mechanism, thus creating two 20 terminals for the wire *b* in each box. A central spring contact 31 is disposed between the contacts 28 and 30, and is adapted to contact with either of said contacts 28 or 30. 25 A bell crank or lever 32 is connected to the spring contact 31, and is operated from the mechanism by means of which the code wheel 26 is rotated, so that when the movement of the box first begins to operate, the contact 31 30 is moved. This contact 31 is connected directly to the wire *b* of the circuit (see Fig. 1), and when it is moved from engagement with either contact 28 or 30, the wire *b* is broken. Normally, however, the lever 32 35 holds the contact 31 in engagement with the contact 30, so that the flow of current is through the wire *b*, the contact 30, to the contact 31, and from the contact 31 to the wire *b*'. The first movement, however, of 40 the box, as has been stated, separates the contacts 30 and 31, and causes an instantaneous or slight breaking of the wire *b*, sufficiently to deenergize the relay R and permit the armature 15 to drop away, cutting the relay 45 out of the test circuit and building up the alarm circuit. The rotation of the code wheel 26 operating against the pen 28 causes a series of make and break operations between the contact 28 and the contact 31, thus 50 making and breaking the alarm circuit and causing a code signal to be received on the signal receiving mechanisms 7.

In order to prevent arcing between the contacts 28, 30 and 31, and particularly between the contacts 28 and 31 when sending 55 the code alarm signal, a standard condenser C is bridged between the wires extending into each box 8 and which constitute a loop in the wire *b* and *b*'.

From the foregoing, it is apparent that 60 this system is such that the circuit controller or relay R builds up, from the connections or wires *b*, *b*', *b*'', *b*''', *t*, *t*', *t*'', *t*''', etc., four complete circuits, to-wit, the test circuit, the 65 alarm circuit, the test or trouble alarm cir-

cuit, and two circuit controller or relay re-set circuits.

The test circuit is a normally established circuit and is built up when the armature 15 is held up by the coil 14 of the relay R. As 70 has been stated, this circuit includes either of the batteries T or T', the wire *t*, the wire *b*, the boxes and bells 8 and 7, the wire *b*'', the contacts 9 and 11, the wire *b*''', the contacts 13 and 21, the wire *t*'', the coil 14 of 75 the relay, and the wire *t*', to the opposite side of either battery T or T'.

The alarm circuit is set up when the code wheel of one of the boxes begins to rotate, which causes the contacts 30 and 31 to separate, creating a break in the wire *b* to allow 80 the relay to fall away. This circuit includes the alarm battery B, the wire *b*, the wire *b*'', the contacts 9 and 11, the wire *b*''', the contacts 13 and 10 and the wire *b*'. 85

The test or trouble alarm circuit is built up simultaneously with the alarm circuit just referred to, when the relay R falls away, as illustrated in Fig. 2, and includes either 90 of the batteries T or T', the wire *t*, the test or trouble alarm 18, the contacts 16 and 19, the wire 20 and the wire *t*'.

The circuit controller or relay re-set circuits are successively built up when the contact 23 is forced against the contact 22. The 95 first of these circuits includes either of the batteries T or T', and the battery B, the wire *t*', the coil 14, the wire *t*'', the wire *t*''', contacts 22 and 23, the wire *b*''', the contacts 13 and 10, and wire *b*', through battery 100 B, and the wire *t* to battery T or T'.

After the combined action of the batteries B and T has moved the armature 15 of the relay R, the second re-set circuit is established, including only either of the batteries 105 T or T', the wire *t*', the coil 14 of the relay R, the wire *t*'', the wire *t*''', the contacts 22 and 23, the wire 12, the contacts 9 and 11, the wire *b*'', the bells and boxes 7 and 8, the wire *b*, to the wire *t*, and through the wire *t* 110 to the battery T.

It is therefore apparent that the operation of the relay or of the boxes 8 destroys certain circuits and builds up certain other circuits through the connections between the 115 various mechanisms, and that at no time is a permanent circuit established which retains its integrity irrespective of the operation of the various mechanical or electrical mechanisms therein.

While the preferred form of the present invention has been illustrated and described, it is to be understood that many changes may be made in the circuits, the construction of the boxes 8, and other details of this invention, without departing from the scope and spirit thereof.

What is claimed is:

1. In a fire alarm system, signal sending and receiving mechanisms in series, an alarm 130

battery and a test battery, and means for establishing an alarm circuit through the signal sending and receiving mechanisms and the alarm battery, said means also establishing a test circuit through the signal sending mechanisms and the signal receiving mechanisms with the test battery when the alarm circuit is not established.

2. In an alarm system, signal sending and signal receiving mechanisms, an alarm battery, a test battery, connections between both the alarm and test batteries and the signal receiving and signal sending mechanisms, and means for establishing an alarm circuit through the alarm battery and the signal sending and receiving mechanisms, and also a normal test circuit through the test batteries and the signal sending and signal receiving mechanisms which is destroyed upon the establishment of said alarm circuit.

3. In an alarm system, signal sending and signal receiving mechanisms, an alarm source of current supply and a test source of current supply, connections between both sources of current supply and the signal sending and receiving mechanisms, and means for establishing a circuit with said connections including the alarm source of current supply and the signal sending mechanisms and signal receiving mechanisms, or the test source of current supply and the signal receiving or signal sending mechanisms.

4. In an alarm system, signal sending and signal receiving mechanisms, an alarm battery, a test battery, connections between both of said batteries and said signal sending and receiving mechanisms, and means for building up an alarm circuit from said connections including the alarm battery and the signal receiving and sending mechanisms, or building up a test circuit from said connections including the test battery and the signal sending and receiving mechanisms.

5. In an alarm system, signaling mechanism, a test battery, an alarm battery, a test alarm, connections between said batteries, test alarm and said signaling mechanism, and means for building up an alarm circuit from said connections including the signaling mechanism and alarm battery and excluding the test battery from said alarm circuit.

6. In an alarm system, signaling mechanism, a test battery, an alarm battery, a test alarm, connections between said batteries, test alarm and said signaling mechanism, and means for building up an alarm circuit from said connections including the signaling mechanism and alarm battery and excluding said test battery, or building up a test circuit including the test battery and the signaling mechanisms and excluding said alarm battery.

7. In an alarm system, signaling mechanism, a test battery, an alarm battery, a test

alarm, connections between said batteries, test alarm and said signaling mechanism, means for building up an alarm circuit from said connections including the signaling mechanism and alarm battery, or building up a test circuit including the test battery and the signaling mechanisms, and means for operating the test alarm from the test battery upon the breaking of the test circuit so built up.

8. In an alarm system, the combination with a signal sending mechanism, of a signal receiving mechanism, a test battery, an alarm battery, connections between both of said batteries and said signal sending and receiving mechanisms, and means for normally building up a test circuit including the test batteries and signal sending and receiving mechanisms and excluding the alarm battery.

9. In an alarm system, the combination with a signal sending mechanism, of a signal receiving mechanism, a test battery, an alarm battery, connections between both of said batteries and said signal sending and receiving mechanisms, means for normally building up a test circuit including the test batteries and signal sending and receiving mechanisms, and means whereby the operation of the signal sending mechanism operates the last said means to establish an alarm circuit including the signal sending mechanism and signal receiving mechanism and the alarm battery and excluding the test battery.

10. The combination with a signaling mechanism, of an alarm battery and a test battery, a relay, connections between said batteries and said signaling mechanisms including said relay, and means operable by said relay for normally establishing a test circuit including the test battery and the signaling mechanisms and excluding the alarm battery.

11. The combination with signaling mechanisms of an alarm battery and a test battery, a relay, connections between said batteries and said signaling mechanisms including said relay, and means operable by said relay for building up an alarm circuit from said connections including the signaling mechanisms and the alarm battery and excluding the said test battery.

12. The combination with signaling mechanisms, of an alarm battery and a test battery, a relay, connections between said batteries and said signaling mechanisms including said relay, and contacts operated by such relay for building up a test circuit from the connections including the signaling mechanisms and test battery and excluding the alarm battery.

13. The combination with signaling mechanisms, of an alarm battery and a test battery, a relay, connections between said bat-

5 teries and said signaling mechanisms including said relay, and contacts operated by the relay for building up an alarm circuit including the alarm battery and signaling mechanisms and excluding the said test battery.

10 14. In an alarm system, the combination with a signal sending mechanism and a signal receiving mechanism, of an alarm battery, a test battery, a relay, and means whereby the armature of the relay is held up by the test battery aforesaid completing a test circuit through the test battery, the signal sending and receiving mechanisms and the relay to the exclusion of the alarm battery.

15 15. In an alarm system, the combination with a signal sending mechanism and a signal receiving mechanism, of an alarm battery, a test battery, a relay, means whereby the armature of the relay is held up by the test battery aforesaid completing a test circuit through the test battery, the signal sending and receiving mechanisms and the relay, and means whereby the operation of a signal sending mechanism deenergizes the relay, creating an alarm circuit including the alarm battery and the signal sending and receiving mechanisms and excluding 20 said test battery from said alarm circuit.

25 16. In an alarm system, a signal sending mechanism and a signal receiving mechanism, an alarm battery, a trouble battery, a relay, electrical connections between the relay, the signal sending mechanism, the signal receiving mechanism, the test battery and the alarm battery, means operable by the relay when energized for building up a test circuit of said connections including 30 the test battery, the relay and the signal sending and receiving mechanisms to the exclusion of said alarm battery, and other means for building up an alarm circuit from said connections when said relay is deenergized including the alarm battery and the signal sending and receiving mechanisms and excluding said test battery.

35 17. An alarm system comprising a signal sending mechanism and a signal receiving mechanism, a test or trouble alarm, an alarm battery, a test battery, a relay, electrical connections between the relay and both of the batteries aforesaid, the test or trouble alarm and the signal sending and receiving mechanisms, means operable when the relay is energized for building up a test circuit of said connections including the relay, the test battery and the signal sending and receiving mechanisms, and further 40 means operable when the relay is deenergized for building up a test or trouble alarm circuit from said connections, including the test battery and the test or trouble alarm.

45 18. An alarm system comprising a signal sending mechanism and a signal receiving

mechanism, a relay, a test or trouble alarm, an alarm battery and a test or trouble battery, electrical connections between the relay, both of the batteries aforesaid, the test or trouble alarm and the signal sending and receiving mechanisms, means operable when the relay is energized for building up a test circuit of said connections, including the relay, the test battery and the signal sending and receiving mechanisms, and means when the signal sending mechanism is operated for building up simultaneously an alarm circuit including the alarm battery and signal sending and receiving mechanisms, and a trouble or test alarm circuit including the test batteries and the test or trouble alarm, including the test batteries and the test or trouble alarm.

50 19. An alarm system comprising a signal sending mechanism and a signal receiving mechanism, a relay, a test or trouble alarm, an alarm battery and a test or trouble battery, electrical connections between the relay, both of the batteries aforesaid, the test or trouble alarm and the signal sending and receiving mechanisms, means operable when the relay is energized for building up a test circuit of said connections, including the relay, the test battery and the signal sending and receiving mechanisms, means when the signal sending mechanism is operated for 55 building up simultaneously an alarm circuit including the alarm battery and signal sending and receiving mechanisms, and a trouble or test alarm circuit including the test batteries and the test or trouble alarm, and means arranged to control the current flow through the electrical connections aforesaid for causing both of said batteries to energize the relay after the deenergization thereof.

60 20. An alarm system comprising a signal sending mechanism and a signal receiving mechanism, a relay, a test or trouble alarm, an alarm battery and a test or trouble battery, electrical connections between the relay, both of the batteries aforesaid, the test or trouble alarm and the signal sending and receiving mechanisms, means operable when the relay is energized for building up a test circuit of said connections, including the relay, the test battery and the signal sending and receiving mechanisms, means when the signal sending mechanism is operated for building up simultaneously an alarm circuit including the alarm battery and signal sending and receiving mechanisms, and a trouble or test alarm circuit including the test batteries and the test or trouble alarm, and means arranged to control the current flow through the electrical connections aforesaid for causing both of said batteries to energize the relay after the deenergization thereof for reestablishing the test circuit aforesaid which was destroyed upon the deenergization of the relay.

21. An alarm system comprising a signal sending mechanism and a signal receiving mechanism, a relay, a test or trouble battery, an alarm battery, electrical connections between both of the batteries aforesaid, the relay and the signal sending and receiving mechanisms, means operable by the relay for building up a test circuit including the test battery, the relay and the signal sending and receiving mechanisms and excluding said alarm battery, and means whereby the signal sending mechanism may deenergize the relay to build up an alarm circuit including the alarm battery and the signal sending and receiving mechanisms and excluding the test battery.

22. An alarm system comprising a signal sending mechanism and a signal receiving mechanism, a relay, a test or trouble battery, an alarm battery, electrical connections between both of the batteries aforesaid, the relay and the signal sending and receiving mechanisms, means operable by the relay for building up a test circuit including the test battery, the relay and the signal sending and receiving mechanisms, a trouble or test alarm, and means whereby the breaking of the connections of the test circuit aforesaid builds up from said connections a test or

trouble alarm circuit including the test battery and the trouble or test alarm.

23. An alarm system comprising a signal sending mechanism, a signal receiving mechanism, a relay, a test battery and a trouble battery, electrical connections between both of said batteries, the relay and the signal sending and receiving mechanisms, means operable by the relay when the latter is energized for establishing a test circuit including the relay, the test battery and the signal sending and receiving mechanisms, means whereby the deenergization of the relay builds up from said connections an alarm circuit including the alarm battery and the signal sending and receiving mechanisms, and simultaneously with a trouble or test alarm circuit including the test battery, and means for re-setting or reenergizing the relay for again establishing the test circuit aforesaid.

In testimony whereof, I have hereunto set my hand in the presence of two subscribing witnesses, on this the 15th day of December, A. D. 1914.
